UNITED STATES PATENT OFFICE.

ARTHUR L. WILDER, OF WETHERSFIELD, CONNECTICUT, ASSIGNOR TO PRATT & WHITNEY COMPANY, OF NEW YORK, N. Y., A CORPORATION OF NEW JERSEY.

GEAR GRINDER.

Application filed April 18, 1924. Serial No. 707,514.

This invention relates to gear grinders and particularly to gear grinders adapted to accurately grind tooth curves of gears at a high rate of production and operating upon 5 a generating principle.

An object of the present invention is to provide improved means for rolling a gear blank past one or more grinding wheels and to provide improved means for indexing the 10 gear blank at the end of each rolling movement.

Another object of the invention is to provide an indexing mechanism comprising a constantly rotating member in the form of a 15 worm, this being adapted to mesh with a gear on the work spindle.

Another object of the invention is to provide means for controlling the movements of the wheels to feed them in a direction parallel 20 to the movement of the gear blank spindle while the blank is being continuously rolled and indexed.

A further object of the invention is to provide mechanism which eliminates the 25 necessity for flexible bands to obtain the rolling movements of the gear blank during operation.

Finally, it is an object to provide a mechanism permitting the operation of grinding 30 spur gears to be carried out automatically after the blank is loaded in the machine.

With these and other objects in view, my invention consists in the features of construction and operation set forth in the following specification and illustrated in the 35 accompanying drawings.

In the accompanying drawings annexed hereto and forming a part of this specification, I have shown my invention embodied 40 in a spur gear grinding machine, but it will be understood that the invention can be otherwise embodied and that the drawings are not to be construed as defining or limiting the scope of the invention, the claims appended to this specification being relied upon 45 for that purpose.

In the drawings:—

Figure 1 is a plan view of the complete 50 gear grinding machine, parts being broken away to more clearly indicate the means for operating the work supporting slide.

Fig. 2 is a front elevation of the machine, parts being shown in section to more clearly indicate their construction, the position of

the wheels being diagrammatically indicated 55 by dotted outlines.

Fig. 3 is a transverse vertical sectional view taken substantially on line 3—3 of Fig. 1.

Fig. 4 is a detail of the improved indexing mechanism shown on a larger scale.

Figs. 5 and 6 are views of different portions of the constantly rotating member of the indexing mechanism.

In the above mentioned drawings, I have 65 shown but one embodiment of the invention which is now deemed preferable, but it is to be understood that changes and modifications may be made within the scope of the appended claims without departing from the 70 spirit of the invention.

Briefly, and in its broadest aspect, my invention comprises the following principal parts: first, a base; second, one or more wheel heads mounted adjustably thereon and 75 adapted to support independently adjustable grinding wheels; third, a work supporting slide adapted to be reciprocated by an adjustable crank, or other means, so that it may be moved through any predetermined 80 distance determined by the particular gear being ground; fourth, a work spindle rotatably mounted on the slide and adapted to support a gear blank with its axis in alignment with the spindle; fifth, a fixed rack in 85 the base adapted to mesh with a master gear on the work spindle preferably corresponding in pitch diameter and number of teeth to the blank being ground; sixth, another gear on the spindle preferably positioned 90 just below the master gear and corresponding to the gear blank and adapted to be engaged by a rotating member of special form at each cycle of operations of the machine; seventh, means to feed the wheels in a direction parallel to the direction in which the blank is rolled during the grinding operation; and eighth, means controlling the rotation of the indexing member so that it will 95 be rotated in timed relation to the reciprocating movements of the work supporting 100 slide.

Referring more in detail to the figures of the drawings, I provide a base 10 having thereon wheel supporting slides 11 preferably mounted upon a horizontal surface of the base and preferably resting upon suitable ball bearings 12. Preferably, two of these 105

slides 11 are provided, each having a wheel head 13 on which a rotatable abrasive wheel 14 is positioned. These slides 11 are similar to each other but oppositely disposed, so that but one of these slides and its wheel head requires specific description.

- On the upper surface of the slide 11 is mounted a member 15 preferably pivotally supported and adapted to be secured in any 10 adjustable angular position by the clamping screws 16 shown in Figs. 1 and 3. This member 15 is adapted to be pivoted about the stud 17 shown in Fig. 1. On the upper surface of this member 15 are suitable ways 15 engaged by corresponding ways of the lower surface of a member 19. The direction of movement of this slide or member 19 is preferably exactly parallel to the work engaging plane of the grinding wheel 14. 20 On the upper surface of this member 19 are suitable ways 20 disposed at right angles to the ways 18 above mentioned. On these is adapted to be adjusted the wheel head 13 carrying a spindle 22 which in turn carries 25 the abrasive wheel 14. To rotate this wheel 14, a motor 23 is carried on the head 13 which is in driving connection with the wheel spindle 22 by means of a belt 24 passing over the pulleys 25 and 26 shown in Fig. 1. 30 It will be seen from the above description that a mounting is provided for the wheels 14 permitting them to be adjusted in any direction, either longitudinally, transversely or angularly, relative to the blank, and their 35 work engaging surfaces therefore can be properly adjusted for any particular size or form of gear blank A being ground. Also by reason of the slides 11 being mounted on the bearings 12, the wheels 14 may be moved 40 toward or from each other to feed them against the blank being ground. To adjust the wheels 14 by means of the slides 15 and 19, hand wheels 28 and 29 are provided operating screws attached to each of these slides 45 (not shown).

The work blank A is carried upon and actuated by movements of a large, vertically disposed slide 30 carried in suitable bearings 31 in the base 10 on either side of the machine. To aid in supporting the slide 30 an arch 29^a is fixed to the base 10 having ways 50 engaged by the upper portions of the slide 30. This slide 30 at one end is provided with bearing surfaces 32 adapted to be engaged by rollers 33 mounted upon a crank 34. The crank 34 is preferably adjustably mounted, as indicated in Fig. 2, upon the upper end of a vertically disposed shaft 35. The shaft 35 and crank 34 may be adapted to be rotated preferably by means of spiral gears 36 and 37, shown in Figs. 1 and 2.

On this slide 30 is disposed a work supporting and rotating spindle 38, preferably mounted as indicated in Fig. 3, upon a vertical axis and suitably supported in suitable

ball bearings 39 near its upper and lower ends so that it is easily rotated. This work spindle 38 carries a center 40 at one end in alignment with an oppositely disposed center 41 carried in a tail block 42 directly above the 70 spindle 38 and movable with the slide 30. Between these oppositely disposed centers 40 and 41 the work holding arbor 43 may be suitably positioned and rotated with rotation of the work spindle 38 through the driving 75 dog 44 shown in Fig. 3. The work supporting arbor 43 is therefore adapted to be reciprocated while maintained in a vertical position by movements of the slide 30. Also the arbor 43 may rotate with the spindle 38 so 80 that, by means of mechanism presently to be described, the blank A may be given a rolling motion upon any desired diameter.

Mounted near the lower end of the work spindle 38 is a gear 45 preferably corresponding in pitch diameter and number of teeth to the gear A desired to be ground. This is adapted to mesh with a rack 46 fixed to a block 47 mounted within the base 10. This gear 45, the rack 46 meshing with it 90 and the parts associated therewith are made so that they may be readily removed and others substituted so that the machine may be adapted for different types and sizes of gears. Also, to eliminate any lost motion 95 between the teeth of the gear 45 and the rack 46, an auxiliary rack 46^a is provided just below the fixed rack 45 and resiliently urged in one direction by means of the spring 48 shown in Fig. 4. This spring pressed rack 100 46^a constantly urges the teeth of the master gear 45 in one direction against the teeth of the fixed rack 46 and is strong enough to prevent any retrograde movement of the gear 45 during the operative movements of 105 the slide 30 and work spindle 38. By these means, there is no lost motion between the rack 46 and the gear 45 and errors from this source are therefore eliminated.

By means of the fixed rack 46 and the 110 master gear 45 on the spindle 38, reciprocatory movement of the slide 30 will simultaneously rotate the spindle 38, these two movements causing a rolling movement of the master gear 45 and the gear blank A 115 upon their pitch cylinders along the pitch plane of the rack 46.

Also on the work spindle 38 and preferably directly below the master gear 45 referred to above is an indexing gear 50 having a number of teeth preferably exactly equal to the number of teeth in the master gear 45 and the blank A being ground. This rotates and reciprocates with the combined movements of the work spindle 38 120 so that its effective motion is a rolling movement similar to that of the gear 45 and the blank A. This last mentioned gear 50 is adapted to be engaged by the member or worm 51 shown in Figs. 4, 5 and 6. This 125 130

gear 50, however, does not mesh with the member or worm 51 except when the slide 30 has been moved to approximately its limit of movement in one direction. At this point in each cycle of operation, the indexing gear 50 comes into contact with the rotating member 51 and while so engaged the rotating member 51 turns through an angle sufficient to index the gear 50 and also the work spindle 38 through an angle corresponding to one pitch or tooth of the blank A being ground. Movement of the slide 30 in the opposite direction disengages the indexing gear 50 from its worm 51 and causes the master gear 45 to again mesh with the master rack 46 in a slightly different angular or indexed position.

The position of the indexing members 51 relative to the rack 46 is clearly shown in Fig. 4. It will be noted that the member 51 is provided with a helical projection or thread, the width and proportions of which correspond to the teeth of the rack 46. The first convolution of the thread on the member 51 is so spaced from the end of the rack 46 that the master gear 45 will mesh correctly with it.

The form of the indexing worm 51 is clearly shown in Figs. 5 and 6. It is preferably made in two half-portions secured together in any desired manner (not shown). One of the half-portions 51^a is provided with annular grooves similar to those of a circular rack. The other portion 51^b has a number of helically disposed grooves, the two sets of grooves joining each other at the plane where the half-portions meet. Also the helical grooves are of such form that each groove engages adjacent annular grooves of the opposite half-portion 51^a. This member 51 is suitably keyed to the end of a constantly rotating shaft 52 so that it may be rotated at relatively high speed.

From this construction of worm 51, only one-half of which is provided with helical grooves, it will be seen that the gear 50 when it meshes with it will be rotated only while engaging the helical portions. When the gear 50 engages the annular grooved part, it is not rotated. The driving means for the indexing worm 51 may be provided from the main driving shaft 53 through suitable helical gears 54 shown diagrammatically in Fig. 1. The ratio between the reciprocations of the slide 30 and the rotations of the indexing worm 51 are, in the illustrated embodiment, six to one, that is, the indexing worm 51 rotates six times while the crank 34 reciprocating the slide 30 rotates but once. The member 51 is mounted on the block 47 carrying the rack 46, its shaft 52 being rotatably mounted within the block 47. The rotatable indexing member 51 is therefore adapted to be removable with the block 47 and the rack 46. A clutch 52^a per-

mits the shaft 52 to be easily disengaged from its driving shaft.

The gear 50 on the work spindle 38 is engaged by the rotating indexing member 51 only when the spindle 38 has been moved by the slide to approximately its limit of movement in one direction. The indexing member 51 is so positioned and timed that this occurs while the annular grooved portion 51^a is in position to engage the teeth of the gear 50. However, while so engaged and while the member 51 is rapidly rotated, the gear 50 engages the helical grooves 51^b and so the gear 50 is rotated slightly. As the slide 30 moves the spindle 38 on its return stroke, the gear 50 and the spindle 38 have been indexed through the space of one tooth. To accomplish this, the stroke of the slide 30 is adjusted to allow the gear 50 to stay in mesh with the member 51 while it rotates slightly more than one-half revolution. During the period that the member 51 is engaged by the indexing gear 50, the helical projections 51^b are engaged throughout their length.

Referring to Figs. 3 and 4, it will be seen the rotating member is adjacent one end of the rack and below it. While the indexing gear is in engagement with the rotating member, the master gear is out of mesh from the rack so that the spindle can be rotated or indexed.

The feeding action of the wheels 14 relative to the teeth of the gear A being ground is preferably provided for by means to move the slides 11 away from each other to slightly separate the work engaging surfaces of the wheels. For this purpose, I provide a vertical shaft 60 which may be rotated at an extremely slow rate of speed from suitable driving connections from the main driving shaft 53 and which rotates a spiral cam 61 upon its upper end. This spiral cam 61 is engaged by the rear end of a rod 62, the forward end of which bears against the oppositely extending ends of two bell cranks 63. The bell cranks 63 are pivotally mounted in the base 10 about fixed axes 64 and their other and shorter arms 65 engage projections in the form of bearing strips 66 fastened to the under surface of the slides 11. It will be seen from this description that rotation of the spiral cam 61 will force the bell cranks 63 to oscillate slightly, thus forcing the slides 11 away from each other upon the ball bearings 12 provided for them. To return the slides 11 to their normal positions, a spring pressed plunger 67 is provided adapted to bear against an adjustable abutment 68 in the form of a screw in the base 10. To positively limit the outward movement of the slides 11, a screw 69 is provided in the base engaging an abutment 70 on the slides.

To manually operate the feed mechanism

for the slides 11 and wheels 14, a hand wheel 71 is mounted on the end of a shaft 72, the opposite end of which is connected to the driving shaft 73 of a worm in engagement 5 with a worm wheel 74 on the lower end of vertical shaft 60. The shaft 60 and its cam 61 may therefore be rotated by the hand wheel 71 or by means of the main driving shaft 53. To disengage the driving connections 10 from the shaft 53 to the shaft 60, a lever 75 is provided, oscillation of which disengages a worm 76 from a worm wheel 77 forming parts of these connections.

What I claim is:

- 16 1. A gear grinder comprising in combination, a base, a grinding wheel rotatable thereon having a plane blank engaging surface, blank supporting and rotating means, means to simulate a rolling action of the 20 blank upon its pitch circle by movement of said support in a straight line, means to index said blank at the end of its rolling motion in one direction, and means to continuously feed said grinding wheel during 25 the rolling motion of the blank in a direction tangential to the pitch circle of the blank.
2. A gear grinder comprising in combination, a base, a pair of obliquely disposed 30 grinding wheels rotatable thereon, blank supporting and rotating means, means to simulate a rolling action of the blank upon its pitch circle by reciprocatory movement of said support, means to index said blank at 35 the end of its rolling motion in one direction, and means to continuously separate said grinding wheels during the rolling motion of the blank to effect feeding motions thereof.
3. A gear grinder comprising in combination, a base, a grinding wheel rotatable thereon, blank supporting and rotating means, means to simulate a rolling action of the blank upon its pitch circle by movement 40 of said support, means to index said blank at the end of each of its rolling motions in one direction, and means to continuously feed said grinding wheel during the rolling motion of the blank in a direction tangential to the pitch circle of the blank.
4. A gear grinder comprising in combination, a base, a grinding wheel rotatably and adjustably mounted thereon, a slide, means to reciprocate said slide, a work spindle rotatably mounted on said slide, means to rotate said work spindle simultaneously with movement of the slide so that a rolling motion 55 of a blank on the spindle is simulated, and means to continue the rolling and indexing movements of the blank while the wheel is slowly fed in a direction tangential to the rolling circle of the blank to completely grind the gear teeth to their correct contour.
5. A gear grinder comprising in combination, a base, a pair of oppositely disposed

grinding wheels rotatably and adjustably mounted thereon, a slide, means to reciprocate said slide, a work spindle rotatably mounted on said slide, means to rotate said work spindle simultaneously with movement 70 of the slide so that a rolling motion of a blank on the spindle is simulated, and means to continue the rolling and indexing movements of the blank while the wheels are slowly fed in opposite directions parallel to 75 the direction of the rolling motion of the blank to completely grind the gear teeth to their correct contour.

6. Indexing means for gear grinding machines comprising in combination, means to bodily move a spindle having a gear blank thereon, means on said spindle adapted to intermesh with a rotatable member at the limit of movement of the blank in one direction, and means to rotate said member 85 in timed relation to the movements of the slide whereby a blank on said spindle will be indexed.

7. Indexing means for gear grinding machines comprising in combination, means to bodily move a spindle having a gear blank thereon, means on said spindle adapted to intermesh with a rotatable member at the limit of movement of the blank in one direction, a helical path on said member, and 95 means to rotate said member in timed relation to the movements of the slide.

8. Indexing means for gear grinding machines comprising in combination, means to bodily move a spindle having a gear blank 100 thereon, means on said spindle adapted to intermesh with a rotatable member at the limit of movement of the blank in one direction, an annular path on a portion of the periphery of said rotatable member and a 105 helical path on another portion of the periphery of said member, and means to rotate said member in timed relation to the movements of the slide.

9. Indexing means for gear grinding machines comprising in combination, means to bodily move a spindle having a gear blank thereon, means to effect a rolling movement 110 of said blank, a member rotatably mounted adjacent a gear on said spindle, and means to rotate said member in timed relation to movements of the spindle, said member and gear being in mesh at each movement of the spindle in one direction whereby said gear and spindle may be indexed.

10. A blank actuating and indexing mechanism for gear grinding machines comprising in combination, a reciprocating slide having a rotatably mounted spindle thereon, a fixed rack, a gear on the spindle engaging 125 said rack whereby movement of the slide will cause rolling movements of a blank on said spindle, a second gear on said spindle, and means adapted to be engaged therewith to index the spindle when said first men- 130

tioned gear is out of mesh with said rack.

11. A blank actuating and indexing mechanism for gear grinding machines comprising in combination, a reciprocatory slide 5 having a rotatably mounted spindle thereon, a fixed rack, a gear on the spindle engaging said rack whereby movement of the slide will cause rolling movements of a blank on said spindle, a second gear on said spindle, and 10 constantly rotating means adapted to be engaged therewith to index the spindle each time said slide approaches its limit of movement in one direction.

12. A blank actuating and indexing mechanism for gear grinding machines comprising in combination, a reciprocatory slide 15 having a rotatably mounted spindle thereon, a fixed rack, a gear on the spindle engaging said rack whereby movement of the slide 20 will cause rolling movements of a blank on said spindle, a second gear similar to the first gear on said spindle, and means adapted

to be engaged therewith at the limit of movement of the slide in one direction to index the spindle, said first mentioned gear being 25 out of mesh with said rack when the blank is being indexed.

13. A blank actuating and indexing mechanism for gear grinding machines comprising in combination, a reciprocatory slide 30 having a rotatably mounted spindle thereon, a fixed rack, a gear on the spindle engaging said rack whereby movement of the slide will cause rolling movements of a blank on said spindle, a second gear on said spindle, 35 and rotatable means operated in timed relation to the movement of said slide and engaging said second gear at the end of the movement of the slide in one direction to index the spindle when said first mentioned 40 gear is out of mesh with said rack.

In testimony whereof, I hereto affix my signature.

ARTHUR L. WILDER.
